UNITED STATES PATENT OFFICE

WILLIAM WADDELL, OF DETROIT, MICHIGAN, ASSIGNOR, BY MESNE ASSIGNMENTS, TO
CONTINENTAL AIRCRAFT ENGINE COMPANY, A CORPORATION OF DELAWARE

INTERNAL COMBUSTION ENGINE

Application filed February 25, 1930. Serial No. 431,268.

My invention relates to an internal combustion engine and more particularly relates to means for retaining the accessory drive gears of a radial engine in place, my device being especially constructed for use with aircraft engines of the radial type, though obviously the principle of my invention may be embodied in engines other than those adapted for use with aircraft.

10 In the manufacture of aircraft engines of the radial type, and especially with that type of engine embodied in the copending application of Archie M. Niven for internal combustion engine, Serial No. 405,476 filed November 7, 1929, owned by assignee company, wherein the accessory drive gears are carried by a wall extending transversely to the longitudinal axis of the crankshaft, it has been found desirable to omit the spring locking 20 rings that are sprung into annular grooves carried by the hubs of the accessory drive gears, in order to facilitate the assembly and to reduce manufacturing costs. However, when repairing the engine, it must sometimes be turned on end and consequently the said accessory drive gears are free to move endwise or longitudinally of the engine unless some means are provided for retaining the said gears in place.

30 It is the object of my invention to facilitate the manufacturing and maintenance of an internal combustion engine of the radial type by providing means for retaining said accessory drive gears in place and to restrain 35 the same from falling out, when the engine is turned on end.

A further object of my invention is to decrease the manufacturing costs of a radial internal combustion engine by providing a 40 simplified accessory driving gear assembly that may be readily and easily assembled with the engine as well as economically manufactured.

A still further object of my invention is to 45 facilitate the assembly or disassembly of the accessory driving gears of a radial engine by providing retaining means to which access may be readily had for simultaneously engaging said gears to restrain the same from endwise or longitudinal movement with re-

spect to the engine and to provide means that may be economically manufactured for locking the retaining means in place.

For a more detailed understanding of my invention, reference may be had to the accompanying drawings which illustrate one form of my invention, and in which:

Fig. 1 is a vertical longitudinal sectional view of the rear portion of a radial internal combustion engine constructed in accordance with my invention,

Fig. 2 is a rear elevational view of the accessory driving mechanism taken substantially on the line 2—2 of Fig. 1,

Fig. 3 is a detail view of the lock washer,

Fig. 4 is a detail view of a thrust washer, and

Fig. 5 is an enlarged detail sectional view of the rear end portion of the crankshaft showing the retainer disc secured thereto.

My invention is adapted to be associated with an internal combustion engine of the radial type especially adapted for use with aircraft, which engine includes a crankcase 10 provided with a transverse wall 11 for closing the open rear end thereof, and a crankshaft 12 supported by and extended through said wall. The rear end of the crankshaft is externally splined and a crankshaft starter gear 13 is splined to the crankshaft to the rear of said wall 11. A plurality of accessory driving gears are supported by and to the rear of said wall, said crankshaft starter gear and accessory driving gears preferably lying in a common plane extending transversely of the crankshaft and parallel to the plane of the wall. Preferably the accessory driving gears include a starter gear 14, the magneto driving gears 15 and the pump gears 16, the starter and magneto gears being arranged to mesh with the crankshaft starter gear.

The starter and magneto gears are provided with hubs 17 that are rotatably supported in bushings 18 carried by the wall 11. No locking means are carried by the hub or bushing for preventing endwise displacement of the gears when the engine is turned on end. Instead thereof, I have provided a retaining disc 20 that is constructed and ar-

ranged to restrain the said gears from endwise displacement. The disc has a diameter greater than the diameter of the crankshaft starter gear, and is secured to the rear end 5 of the crankshaft to the rear of the wall 11 and the crankshaft starter gear 13. It will be seen by referring to Fig. 2 how the outer rim of the disc 20 slightly overlies a portion of the adjoining magneto driving 10 gears 15 and the starter gear 14. These gears 14 and 15 are permitted to rotate freely because of the slight clearance between the rim of the disc and the gears.

The rear portion of the crankshaft 12 is 15 hollow and the end portion is bored out and internally threaded as at 21 to adjustably receive an externally threaded nut 22 which secures the disc 20 to the crankshaft. A thrust washer 23 is located immediately adjacent the end of the crankshaft and is provided with a notch 24. A thin sheet metal lock washer 25 interposed between the head 26 of the nut 22 and thrust washer 23 is provided with a tongue 27 that is bent forwardly 20 and inserted through the notch 24 in the thrust washer and into one of the splines carried by the crankshaft starter gear. One or more additional tongues 28 are carried by 25 the lock washer which may be bent back and engaged with one or more of the flat side faces of the head of the nut to lock the nut and prevent the same from working loose.

It may be noted that I have provided a very simple means for readily locking the accessory driving gears to the wall 11 of the crankcase structure, such locking means being so constructed and arranged that access may be very readily had thereto to facilitate the initial assembly of the engine as well as 30 to permit the engine to be set on end while being repaired or assembled without the danger of the accessory drive gears falling out. This structure may be readily and economically manufactured and assembled to a 35 radial internal combustion engine, with a minimum of labor.

Although I have illustrated but one form of my invention and have described in detail but a single application thereof, it will be 40 apparent to those skilled in the art to which my invention pertains that various modifications and changes may be made therein without departing from the spirit of my invention or from the scope of the appended 45 claims.

What I claim as my invention is:

1. In an internal combustion engine having a crankcase and a crankshaft supported thereby, a plurality of gears, means carried 50 by said crankcase for supporting said gears in a plane substantially perpendicular to the longitudinal axis of the crankshaft, and means carried by said crankshaft and adapted for engagement with said gears to prevent 55 endwise displacement thereof.

2. In an internal combustion engine having a crankcase and a crankshaft supported thereby, a plurality of gears, means carried by said crankcase for supporting said gears in a plane substantially perpendicular to the longitudinal axis of the crankshaft, and means adapted for engagement with the faces of said gears to prevent endwise displacement thereof. 50

3. In an internal combustion engine having a crankcase and a crankshaft supported thereby, a plurality of gears, means carried by said crankcase for supporting said gears in a plane substantially perpendicular to the longitudinal axis of the crankshaft, and means overlapping the faces of said gears to prevent endwise displacement thereof. 55

4. In an internal combustion engine having a crankcase and a crankshaft supported thereby, a plurality of gears, means carried by said crankcase for supporting said gears in a plane substantially perpendicular to the longitudinal axis of the crankshaft, and means secured to the crankshaft and arranged to overlie a portion of the faces of said gears to prevent endwise displacement thereof. 60

5. In an internal combustion engine having a crankcase and a crankshaft supported thereby, a plurality of gears, means carried by said crankcase for supporting said gears in a plane substantially perpendicular to the longitudinal axis of the crankshaft, and a retaining disc secured to the crankshaft and arranged to overlie a portion of the faces of said gears to prevent endwise displacement thereof. 65

6. In an internal combustion engine having a crankcase and a crankshaft provided with a crankshaft starter gear, a plurality of accessory driving gears operatively connected with the crankshaft starter gear and positioned in substantially the same plane as said crankshaft starter gear, and a retaining disc secured to the crankshaft to the rear of the end thereof and having a diameter greater than the diameter of the crankshaft starter gear, said retaining disc arranged to overlie a portion of the faces of said accessory driving gears to prevent endwise displacement thereof. 70

7. In an internal combustion engine having a crankcase and a crankshaft, a crankshaft starter gear splined to said crankshaft, a plurality of accessory driving gears operatively connected with the crankshaft starter gear and positioned in substantially the same plane as said crankshaft starter gear, a retaining disc secured to the rear end of the crankshaft and having a diameter greater than the diameter of the crankshaft starter gear to thereby overlie a portion of the rear faces of said accessory driving gears to prevent endwise displacement thereof, fastening means for securing the disc to the crank- 75

shaft, and locking means for locking said fastening means to said crankshaft.

8. In an internal combustion engine having a crankcase and a crankshaft, a crankshaft starter gear splined to said crankshaft, a plurality of accessory driving gears operatively connected with the crankshaft starter gear and positioned in substantially the same plane as said crankshaft starter gear, a retaining disc secured to the rear end of the crankshaft and having a diameter greater than the diameter of the crankshaft starter gear to thereby overlie a portion of the rear faces of said accessory driving gears to prevent endwise displacement thereof, a nut adjustably secured to said crankshaft for securing said retaining disc thereto, and a lock washer therefor provided with an inwardly bent tongue arranged to engage in one of the splines carried by said crankshaft starter gear to lock the nut to said crankshaft.

In testimony whereof I affix my signature.
WILLIAM WADDELL.
